 PC(57) **CLAIM**

What is claimed is the ornamental design for a price tag molding, as shown and described.

DESCRIPTION

FIG. 1 is a front perspective view of a price tag molding, showing our new design;

FIG. 2 is a rear perspective view thereof;

FIG. 3 is a front elevation view thereof;

FIG. 4 is a right side elevation view thereof, the left side elevation view being a mirror image thereof;

FIG. 5 is a top plan view thereof;

FIG. 6 is a bottom plan view thereof, and,

FIG. 7 is a rear elevation view thereof.

The broken line portion of the drawings show a symbolic break that forms no part of the claimed design. The article is shown with a symbolic break in its length. The appearance of any portion of the article between the break lines forms no part of the claimed design.
